BOTTLE WARMER

David Chapman, Chicago, Ill., assignor to HanksCraft
Company, Reedsburg, Wis., a corporation of Wisconsin

Application November 2, 1955, Serial No. 38,695

Term of patent 14 years

(Cl. D81—10)

Fig. 1.

Fig. 2.

Fig. 1 shows a perspective view of a bottle warmer embodying the design of the present invention; and

Fig. 2 shows a top plan view of the bottle warmer shown in Fig. 1.

Both sides of the bottle warmer are alike except that only the side shown in Fig. 1 has an opening for the electric cord.

I claim:

The ornamental design for a bottle warmer, as shown and described.
